SLEEVE ANCHOR

Thomas G. Bixby, Valparaiso, and Harrison R. Holman,
South Bend, Ind., assignors to Phillips Drill Company,
Michigan City, Ind., a corporation of Illinois

Filed Apr. 15, 1968, Ser. No. 11,460

Term of patent 14 years

U.S. Cl. D54—9
Int. Cl. D8—04

FIG. 1 is a front perspective view of a sleeve anchor showing our new design;

FIG. 2 is a sectional view taken through the said sleeve anchor along the line 2—2 of FIG. 1 and in the direction indicated generally.

The dominant feature of our design resides in the multiple strip and slot arrangement at the center of the sleeve anchor as shown in the figures.

We claim:

The ornamental design for a sleeve anchor, substantially as shown and described.
